US0D1030122S

(12) **United States Design Patent** (10) **Patent No.:** **US D1,030,122 S**
(45) **Date of Patent:** **** Jun. 4, 2024**

(54) **LAMP**

(71) Applicant: **JOHN POMP STUDIOS, INC.**,
Philadelphia, PA (US)

(72) Inventor: **John Pomputius**, Philadelphia, PA (US)

(73) Assignee: **JOHN POMP STUDIOS, INC.**,
Philadelphia, PA (US)

(**) Term: **15 Years**

(21) Appl. No.: **29/747,759**

(22) Filed: **Aug. 25, 2020**

(51) LOC (14) Cl. **26-05**

(52) U.S. Cl.

USPC **D26/125**; D26/88

(58) **Field of Classification Search**

Reisman, PC

(57) **CLAIM**

The ornamental design for a lamp, as shown and described.

DESCRIPTION

FIG. 1 is a front bottom perspective view thereof;
FIG. 2 is front view thereof;
FIG. 3 is a rear view thereof;
FIG. 4 is a right view thereof;
FIG. 5 is a left view thereof;
FIG. 6 is a top view thereof;
FIG. 7 is a bottom view thereof; and,
FIG. 8 is a front top perspective view thereof.
The dashed broken lines indicate portions of the lamp that
form no part of the claimed design.

1 Claim, 7 Drawing Sheets
